corporation of Delaware

Application March 16, 1932, Serial No. 599,111

4 Claims. (Cl. 123—187.5)

This invention relates to apparatus for facilitating the starting of internal combustion engines from the cold during cold weather, and resides in apparatus by which fuel may be introduced into the induction systems of internal combustion engines at points close to the intake ports under starting conditions, and in means for operating and controlling the operation of the apparatus.

For a better understanding of the nature and objects of the present invention, reference is made to the following specification in which there are described the preferred embodiments of my invention which are illustrated in the accompanying drawings.

15 In the accompanying drawings:

Figure 1 is a view showing one form of my apparatus for facilitating the starting of an internal combustion engine applied to the propelling engine of an automotive vehicle.

20 Figure 2 is an enlarged fragmentary view of the carburetor and associated parts of the engine shown in Figure 1.

25 Figure 3 is a view showing a second form of my apparatus for facilitating the starting of an internal combustion engine applied to the propelling engine of an automotive vehicle.

Figure 4 is an enlarged fragmentary view of the carburetor and associated parts of the engine shown in Figure 3.

30 Figure 5 is an enlarged fragmentary section taken on the line 5—5 of Figures 1 and 3.

Figure 6 is an enlarged fragmentary section taken on a line parallel to the line 6—6 of Figure 3 and in the horizontal plane which includes the 35 axis of the manifold 22.

In the automotive vehicle which is illustrated in the drawings, there is installed an internal combustion propelling engine 1 on which there is mounted a carburetor 2 into which air enters through the conduit 3 and from which a combustible mixture of fuel and air is discharged through the riser 4 which is connected to the intake ports of the engine by an extension 5 and a manifold 6. To regulate the volume of air which enters the carburetor through the conduit 3, there is provided within the conduit 3 a choke valve 7 of the butterfly type which is mounted on a shaft 8 to which is secured an operating arm 9 which is adapted to be manipulated from the driver's seat of the vehicle through a rod 10. To regulate the volume of combustible mixture which is discharged through the riser 4, there is provided in the extension 5 a throttle valve 11 (Fig. 4) of the butterfly type which is mounted on a shaft 12 to 55 which is secured an operating arm 13 which is

adapted to be manipulated from the driver's seat of the vehicle through any suitable linkage. There is also installed on the engine 1 an engine-operated fuel pump 14 whose discharge side is connected to the float bowl 15 of the carburetor 5 by a pipe 16 and a T-coupling 17.

In the form of the invention which is illustrated in Figures 1 and 2 of the drawings, the branch of the T-coupling 17 which is not connected to the pipe 16 or the float bowl 15 is connected to one end of a pipe 18 whose opposite end opens into the inlet side of a valve housing 19. To the discharge side of the valve housing, there is connected one end of a pipe 21 whose opposite end opens into the middle of a manifold 22 on 15 which there are provided branches 23. Into each of the branches of the intake manifold adjacent the intake port with which it communicates, there extends a nozzle 24 which is connected to one of the branches 23 of the manifold 22 and whose 20 discharge end is directed toward the adjacent intake port, as shown in Figure 5.

In the valve housing 19, there is formed an inlet chamber 25 which communicates with the pipe 18 and a discharge chamber 26 which communicates with the pipe 21. A poppet valve 27, which is located within the inlet chamber 25 and is carried by a stem 28, which extends through a port 29 which connects the chambers 25 and 26 and through the outer wall of the chamber 26, 30 is urged by a coil spring 30 from the position in which it is shown in dotted lines in Figure 2, in which the port 29 is open, to that in which it is shown in solid lines in Figure 2, in which it is seated on the walls of and closes the port 29. 35

Any suitable manually and/or automatically operable mechanism may be provided for moving the valve 27 from the position in which the port 29 is closed to that in which it is open, but I prefer, as shown in the drawings, to interconnect 40 the valve 27 with the choke valve operating mechanism so that when the choke valve approaches fully closed position the port 29 will be opened. To this end, I provide in the choke valve operating arm 9 and opening 31 through which the 45 end of the valve stem 28 extends and on the stem 28 an abutment 32 with which the choke valve operating arm is adapted to contact when the choke valve approaches fully closed position.

In starting the engine shown in Figures 1 and 2 of the drawings from the cold, the operator will move the choke valve 7 toward the position in which it closes the air intake conduit 3 by moving the choke valve operating arm 9 in a counter-clockwise direction before cranking the engine in 55

order to increase the ratio of fuel to air in the combustible mixture discharged from the riser 4. In cold weather, it is difficult, if not impossible, although the choke valve be in fully closed position, to convey from the carburetor to the cylinders of the engine by the suction of the engine a combustible mixture in which the ratio of fuel to air is sufficiently great to insure that the engine will start quickly and easily. My invention eliminates this difficulty and insures quick and easy starting of the engine during cold weather because, when the choke valve 7 approaches fully closed position, the choke valve operating arm 9 engages the abutment 32 on the valve stem 28 and moves the valve 27 toward the position in which it is shown in dotted lines in Figure 2. When under these conditions the engine is cranked, fuel is forced by the pump 14, through the pipe 16, the T-coupling 17, the pipe 18, the valve housing 19, the pipe 21, the manifold 22, the branches 23 and the nozzles 24, into the branches of the intake manifold 6 adjacent the cylinder intake ports and is carried by its own velocity and the current induced by the suction of the engine into the engine cylinders. Thus it is insured that a combustible mixture in which the ratio of fuel to air is sufficiently great to insure quick and easy starting of the engine will reach the cylinders of the engine when the engine is so cold that the suction of the engine cannot alone be relied upon to do it.

In the form of my invention which is illustrated in Figures 3, 4 and 6 of the drawings, the branch of the T-coupling 17, which is not connected to the pipe 16 or the float bowl 15, is connected to one end of a pipe 18 whose opposite end opens into the inlet side of a valve housing 20. To the discharge side of the valve housing 20, there is connected one end of a pipe 56 on whose opposite end there is formed a nozzle 57 which extends into the larger end of funnel-shaped fitting 58 as shown in Figure 6. The smaller end of the fitting 58 is connected by a coupling 59, in which there is provided an air bleed opening 60 and a regulating screw 61 therefor, to one end of a pipe 62 whose opposite end is connected to the middle of a manifold 22 which is similar to the part in Figures 1 and 2 to which the same reference character is applied and is similarly connected to the intake manifold 6.

In the valve housing 20, there is formed an inlet passage 33 which communicates with the pipe 18 and a discharge passage 34 which communicates with the pipe 56. A conical valve member 35, which is carried by a stem 36 which extends to a point without the valve housing 20 and carries on its outer end an abutment 37, is urged by a coil spring 39 from the position in which it is shown in dotted lines in Figure 4, in which the port 38 which connects the passages 33 and 34 is open, to that in which it is shown in solid lines in Figure 4, in which it is seated on the walls of and closes the port 38.

Any suitable manually and/or automatically operable mechanism may be provided for moving the valve member 35 from the position in which the port 38 is closed to that in which it is open, but I prefer, as shown in the drawings, to interconnect the said valve member with the choke valve operating mechanism so that, when the choke valve approaches fully closed position, the port 38 will be opened. To this end, I provide on the body of the carburetor 2 a pivot element 40 on which there is mounted a lever 41 in whose arm 42 there is provided an opening 43

through which the valve stem 36 extends, and whose arm 44 engages a cam 45 carried by the choke valve shaft 8. The cam 45 is so designed that when the choke valve 7 is moved toward closed position it will rock the lever 41 and when the choke valve approaches fully closed position will bring the arm 42 into engagement with the abutment 37 on the valve stem 36.

In starting the engine shown in Figures 3 and 4 of the drawings from the cold, the operator 10 moves the choke valve 7 toward the position in which it closes the air intake conduit 3 by moving the choke valve operating arm in a counter-clockwise direction before cranking the engine in order to increase the ratio of fuel to air in the combustible mixture discharged from the riser 4. The apparatus shown in Figures 3 and 4 eliminates the difficulty hereinbefore referred to of conveying from the carburetor to the cylinders of the engine a combustible mixture in which the ratio of fuel to air is sufficiently great to insure that the engine will start quickly and easily in cold weather because, when the choke valve 7 approaches fully closed position, the choke valve operating arm 9 through the cam 45 moves the arm 42 of the lever 41 into engagement with the abutment 37 on the valve stem 36 and the valve 35 toward the position in which it is shown in dotted lines in Figure 4. When, under these conditions, the engine is cranked, fuel is forced by the pump 14 through the pipe 16, the T-coupling 17, the pipe 18 and the valve housing 20 into the pipe 56 from which it is sprayed through the nozzle 57 into the enlarged end of the funnel-shaped fitting 58. From the funnel-shaped fitting 58, the spray of fuel is drawn by the suction produced in the cylinders of the engine successively into the coupling 59 (in which it is mixed, if the regulating screw 61 is not in the position in which the bleed opening 60 is closed, with air which enters the coupling through the bleed opening 60), the pipe 62, the manifold 22, and the branches 23 from which it is discharged through the nozzles 24 into the cylinders of the engine. From what has been said, it will be apparent that, by means of the apparatus illustrated in Figures 3 and 4, it is insured that a combustible mixture, in which the ratio of fuel to air is sufficiently great to insure quick and easy starting of the engine, will reach the cylinders of the engine when the engine is so cold that the suction of the engine cannot alone be relied upon to do it and, moreover, that the ratio of fuel to air in the combustible mixture can be adjusted independently of the choke valve 7 by adjustment of the regulating screw 61. If desired, the regulating screw 61 may be adjusted, after the engine is started, to the position in which it closes the bleed opening 60.

In order that the throttle valve 11 may be opened to a predetermined extent when the engine illustrated in Figures 3 and 4 is being started under conditions that render it desirable partially or fully to close the passage 3, I provide on the arm 42 of the lever 41 an extension 46 which carries a set-screw 47 which engages a cam-like extension on the throttle valve operating arm 13, and opens the throttle valve to a predetermined extent when the choke valve 7 is moved toward closed position.

In order to insure that sufficient fuel to form a combustible mixture in which the ratio of fuel to air is sufficiently great to insure quick and easy starting of the engine shown in Figures 3

and 4 will reach the nozzles 24 when the choke valve 7 so closely approaches fully closed position that the port 38 is opened, I consider it preferable to prevent any of the fuel discharged from the 5 pump 14 entering the float bowl 15 under these conditions. To this end, I provide on the body of the carburetor 2 an element 48 which serves as a fulcrum for a lever 49 whose one arm 56 carries a pin 51 which extends through the top of the float bowl and is adapted to engage the lever 52 through which the float 53 operates the needle valve 54, which controls the passage of fuel from the T-coupling 17 into the float bowl. The opposite end 55 of the lever 49 is so located that it 10 will be engaged by the choke valve operating arm 9 when the choke valve approaches fully closed position. When the choke valve 7 approaches fully closed position, the choke valve operating arm 9 will, as previously stated, engage the arm 20 55 of the lever 49 and cause the lever to rock about its fulcrum 48 and, through the pin 51 and the lever 52, move the needle valve 54 into the position in which it closes the passage through which fuel enters the float bowl from the 25 T-coupling 17, and thus cause all of the fuel which is discharged from the fuel pump 14 to enter the pipe 18 and pass therethrough and through the intermediate connecting passages to the nozzles 24.

It will be noted that, since the choke valve operating arm 9 in Figures 1 and 2 does not engage the abutment 32 on the valve stem 28, and the arm 42 of the lever 48 in Figures 3 and 4 does not engage the abutment 37 on the valve stem 36 30 until the choke valve 7 approaches fully closed position, my apparatus for facilitating starting does not function except when the choke valve approaches fully closed position and, consequently, does not affect the operation of the engine on 35 which it is installed except under such conditions as render it necessary or desirable almost completely to close the air intake conduit 3. It will be further noted that, since the fuel pump 14 does not operate except when the crankshaft of 40 the engine is being rotated, no fuel will be discharged from the nozzles 24, although the choke valve 7 is fully closed, unless the crankshaft is being rotated and, consequently, there is no possibility of the apparatus "flooding" the cylinders 45 of the engine on which it is installed.

Although I have shown and described preferred embodiments of my invention, it is to be under-

stood that this has been done by way of example and not by way of limitation and, consequently, that the scope of my invention is to be determined only by the appended claims.

I claim:

1. In an internal combustion engine, an induction system, including a carburetor in which there is incorporated a fuel reservoir, for supplying a combustible mixture to the cylinders of the engine, a pump for supplying fuel to the reservoir, means, including the pump, for introducing fuel into the induction system between the carburetor and the intake ports of the cylinders, and means to prevent introduction of fuel into the reservoir during the operation of the mentioned means. 15

2. In an internal combustion engine, an induction system, including a carburetor, for supplying a combustible mixture to the cylinders of the engine, a valve for controlling the admission of air to the carburetor, a valve for controlling the discharge of combustible mixture from the carburetor, means for introducing fuel into the induction system between the carburetor and the intake ports of the cylinders, and means for rendering the mentioned means operative and partially opening the second mentioned valve when the first mentioned valve approaches fully closed position. 20 25

3. In an internal combustion engine, an induction system, including a carburetor, for supplying a combustible mixture to the cylinders of the engine, a valve for controlling the admission of air to the carburetor, means for injecting fuel into the induction system between the carburetor and the intake ports of the cylinders, and means whereby after but not before the mentioned valve has been closed to a predetermined extent further movement thereof toward its closed position renders the mentioned means operative. 30 35

4. In an internal combustion engine, an induction system, including a carburetor, for supplying a combustible mixture to the cylinders of the engine, a valve for controlling the admission of air to the carburetor, means for introducing fuel into the induction system adjacent the intake 40 45 ports of the cylinders, and means whereby after but not before the mentioned valve has been closed to a predetermined extent further movement thereof toward its closed position renders the mentioned means operative whenever the engine is operating. 50

HARRY O. LEUSCHNER.
